[57] CLAIM

The ornamental design for a combined battery powered lantern and fan, as shown and described.

DESCRIPTION

FIG. 1 is a perspective view of a combined battery powered lantern and fan, showing my new design.

FIG. 2 is a front elevational view thereof.

FIG. 3 is a top plan view thereof.

FIG. 4 is a left side elevational view thereof, the right side being a mirror image of that shown.

FIG. 5 is a rear elevational view thereof.

FIG. 6 is a bottom plan view thereof.

FIG. 4

FIG. 5

FIG. 6
